UNITED STATES PATENT OFFICE.

ANTHONY R. SILVERSTON, OF NEW YORK, N. Y., ASSIGNOR TO COKE RECLAMATION CORPORATION, OF NEW YORK, N. Y., A CORPORATION OF NEW YORK.

SEPARATION APPARATUS AND PROCESS.

Application filed November 15, 1924. Serial No. 750,042.

My invention relates to separation process and apparatus, and more particularly to apparatus for separating granular or crushed materials, such for example as for the separation of coke from clinkers, utilizing the principle of a flowing liquid and the different rates of gravitation through the liquid, of the ingredients of different specific gravities.

The objects of the invention are to provide durable and efficient apparatus of the character described, to provide for considerable flexibility in the operation of the apparatus so as to readily adapt it for the separation of different kinds or characters of materials, and to so arrange and construct the apparatus that it may be mounted on a power-driven truck or vehicle to be transported to various places of use and there to be driven by the power unit of the vehicle.

Further objects and advantages of the invention will more fully appear from the following description taken in connection with the accompanying drawings illustrating the two preferred embodiments of the invention.

The invention consists in the novel features, arrangements, construction and combination of parts hereinafter described in connection with said preferred embodiments thereof, and the invention will be more particularly pointed out in the appended claims.

Fig. 1 is a diagrammatic side elevation of the apparatus.

Fig. 2 is a diagrammatic plan view of Fig. 1.

Fig. 3 is a detail plan view of the tank partly in section taken substantially on line 3-3 of Fig. 4.

Fig. 4 is a detail vertical section on larger scale taken on line 4-4 of Fig. 2.

Fig. 5 is a fragmentary detail taken on line 5-5 of Fig. 4.

Fig. 6 is a vertical section of the tank taken on line 6-6 of Fig. 2.

Fig. 7 is an enlarged vertical section taken on line 7-7 of Fig. 2.

Figs. 8 and 9 are fragmentary details of the means for adjusting control plates and locking the same in the desired position.

Figs. 10 and 11 are cross sectional views of a vibrating chute taken on lines 10-10 and 11-11 of Fig. 6.

Figs. 12 and 13 are details of modifications of a coke conveyor.

Figs. 14 and 15 are diagrammatic illustrations showing the apparatus adapted to a motor truck of conventional type, and show-

ing some parts of the rotary sifter not shown in the other figures.

Figs. 16 and 17 are detail views on larger scale showing regulating mechanism applied to a rotary screen.

60

Apparatus for mechanical separation.

Referring to the drawings and more particularly to Figs. 1 and 2.

1 is a supporting tower. Rotary crushers 65 2-2 are mounted on said tower and tracks 3-3 are mounted over said crushers and carry buckets 4-4 adapted to convey material to the crushers. Tracks 5-5 are arranged at a level lower than the crushers 70 and buckets 6-6 are mounted thereon adapted to carry the crushed material to a separating and screening drum 7 which is rotatably mounted on a sub-frame 8 (Figs. 16 and 17) at a slight inclination to the horizontal. The sub-frame 8 is pivotally mounted on the shaft 9 carried by supports 10-10 attached to the frame 11 which is mounted on the supporting tower 1. Parallelogram link frames 12-12' are pivotally attached 75 to the sides of the sub-frame 8 and frame 11 at their opposite upper and lower ends respectively. Screw nuts 13-13 and 13'-13' are pivotally attached to the opposite sides of the link frames 12-12' and are operatively 80 connected by means of screws 14-14' on the ends of which are bevel gears 15-15' in mesh with a second set of gears 16-16' carried by the shaft 17 which is mounted in suitable bearings on the end of sub-frame 8. A 85 sprocket 18 is pinned to the shaft 17, and a chain 19 suitably operated is in engagement with this sprocket to permit of the rotation of the shaft 17 to thereby rotate gears 16-16', 15-15' and screws 14-14' to cause the screw 90 nuts 13-13 and 13'-13' to be moved together or apart respectively. It will be seen that as the respective nuts of the parallelogram frames 12 and 12' are moved together the lengths of the parallelogram frames along 95 their major or vertical axes are increased and the inclination of the sub-frame 8 is increased with respect to the frame 11. Conversely when the screw nuts are moved apart this inclination is decreased.

A spout 20 (Figs. 1, 2 and 17) is provided adjacent the lower end of drum 7 for carrying away particles of material too coarse to pass through the coarsest mesh of the rotary drum 7. Beneath the screen a plurality 100 105 110

of chutes 21 and 22 are provided for keeping the particles of different sizes passing through the different perforations of the drum separated. The chute 21 conducts off 5 the "fines" and chute 22 the coarser material. A conveyor belt 23 is positioned in the chute 22 and extends downwardly therewith into cooperative dumping alignment with a chute 24 (see also Fig. 6) provided with a screen 10 bottom 25 and a delivery end portion 26 provided with a solid bottom. This chute is supported on pivoted links 27-27 attached to a stationary support 28, and is adapted to be shaken by means of link 29, lever 30, pitman 31 and eccentric 32 which is operated 15 in a manner to be described later.

Apparatus for hydrodynamic separation.

A tank 33 (see Figs. 3, 4 and 6), is provided 20 for containing any suitable liquid such for example as water. This tank is enclosed on the four sides by the longitudinally extending side walls 34 and 35 and the end walls 36 and 37. For the sake of brevity in description the ends of the tank at 37 and 36 will be termed the "front" and the "rear" of the tank respectively. A partition 38 (Fig. 3) extends longitudinally of said tank and serves to divide the same into two passages 25 which are in communication with each other around the ends of said partition 38. The bottom of the tank adjacent the side 35 extends back from the end 37 (Fig. 4) horizontally to a point adjacent the rear end of the partition 38 and then extends vertically 30 downward a distance equal substantially to the depth of the end 37, and then continues horizontally to the end 36. The bottom of the tank adjacent the side 34 (Fig. 6) extends 35 back from the front end of the partition 38, extends vertically a distance equal substantially to the depth of the end 37 and then continues horizontally to a point midway longitudinally of said tank, then inclines 40 rearwardly upwardly to a point adjacent the rear end of the partition, forming thereby the bottom portions of a central pocket, and then follows the lines of the bottom adjacent the side 35. The partition 38 extends 45 downwardly and together with the side 34 forms the side walls of this pocket. It will therefore be seen that the front end of the tank forward of the partition, is of uniform depth for the entire width of the tank, and 50 that the rear end of the tank rearward of the partition is of a much greater depth the entire width of the tank. This relatively deep rear portion of the tank acts as a sump and is provided for collecting sediment. The 55 front end of the central pocket formed between the side 34 and partition 38 extended downwardly, will be designated as 39; the bottom of the pocket as 40, and the rearwardly upwardly inclined portion as 41. The 60 bottom of the tank at its least depth will be 65

designated as 42. A separating plate 43 is spaced slightly to the rear of the front end 39 (Fig. 6) and parallel thereto. This plate 43 substantially divides off the front of the central pocket into a chamber which will be referred to hereinafter as 44. An inclined piece 45 (Fig. 7) extends from the partition 38 at the upper part of this chamber downwardly to the junction of the bottom 40 and the side wall 34. A chute 46, preferably of 70 metal, is supported on the incline 45 and passes through an opening in the wall 34, and thence into a pit which will be referred to as 47, and is constructed as follows: 75

Adjacent the central pocket a wall is provided, (see also Fig. 6) the lower part 48 of which is below the level of the said pocket; and three upright walls 49, 50 and 51 in cooperative relation thereto and together with the side wall 34 form a pit which is in communication with the central pocket of the tank through the said opening in the side wall 34. Suitable means is provided for causing the liquid to flow in a predetermined direction as indicated by the arrows (Figs. 80 3 and 4); such for example as the propeller 85 or other suitable water propulsion means 52, mounted on a shaft 53 supported in bearings 54 and 55 mounted respectively on the stand 56 and rear end 36 of the tank. A 85 suitable guard frame 57 shields the propeller from injury, protects the operator from harm and prevents splashing.

Directing means such as deflector vanes 58, 59 and 60 extend vertically the depth of the 100 forward end of the tank and extend transversely across this portion of the tank in a curved path between the ends of the two longitudinal passages of the tank, and are adapted to direct the liquid current in an even flow 105 around the front end of the partition 38 and also to prevent eddy currents in a vertical direction. Adjacent the down stream end of 110 said vertical vanes a series of horizontal vanes, 61, 62 and 63 are mounted and extend across the passage between the side 34 and partition 38, for preventing eddy currents in a horizontal direction. It will therefore be seen that 115 at the downstream edge of said horizontal vanes the current will be flowing in a constant stream of uniform velocity throughout its depth. The liquid flow is therefore divided into sections in both a horizontal and vertical direction, and may be said to be "sectionalized" in vertical and horizontal directions. 120 The vanes 61, 62 and 63 are of different widths, preferably being arranged with progressively increasing widths from top to bottom of the tank. These horizontal vanes are 125 also preferably arranged with their down stream edges staggered, the one at the greatest depth being positioned furthest down stream and the upper ones being progressively farther up stream. The reason for this will be 130 made clear hereinafter.

Adjacent the downstream edge of the horizontal vanes 61, 62 and 63 adjustable liquid flow regulating plates 64, 65 and 66 (Figs. 7 and 6) are carried by the control rods 67, 68 and 69 pivotally supported in suitable bearings in the sides 34 and 35 and the partition 38. These control rods and regulating plates are each mounted respectively adjacent one of the stationary vanes 61, 62 and 63. On the end of each of the rods 67, 68 and 69 is attached respectively a segmental gear rack such as 70—70' and 70'' (Figs. 8 and 9) and latch means such as pawls 71—71' and 71'' are adapted to cooperate with the gear rods to lock the respective plates in any desired position. The ends of the control rods are each provided with square portions 72—72'—72'' to accommodate a crank handle or wrench to allow for the proper individual adjustment of the plates.

The function of these plates 64, 65 and 66 will now be described in connection with the current actuating means, the partition 38, the vertical vanes 58, 59 and 60; and the horizontal vanes 61, 62 and 63.

The propeller or propulsion wheel 52 causes the liquid to flow in a current stream; while the propeller in cooperation with partition 38 causes the fluid to flow in a continuous current stream around the partition. The vertical vanes 58, 59 and 60 straighten out the flow in a vertical direction and the horizontal plates 61, 62 and 63 straighten out the current in a horizontal direction. So that at a point adjacent the downstream edge of the vanes 61, 62 and 63 all parts of the current will flow in a stream of substantially constant velocity and parallel one with another throughout its entire cross section at this point, i. e. it will be "sectionalized," avoiding eddies, swirls etc. Now by means of the adjustable plates 64, 65 and 66 this uniform current may be accurately controlled in a manner best adapted for the separation of the particular material being handled. In the separation of material such as results from combustion of coal in boiler furnaces and with the apparatus arranged as shown it is preferable to have the plates closed—i. e. lowered—to an increasing degree from top to bottom with the top vane preferably entirely open, so that the current at the surface will move horizontally and with greater velocity, while the current at other depths somewhat directed downwardly and will move with progressively decreased velocity. With this adjustment of the vanes the liquid will flow in degrees of greater downward inclination at progressively greater depths commencing just under the surface.

60 *Conveyor means for removing particles from tank.*

Two conveyor means are provided for removing the materials after separation but it is obvious that as many as desirable may be

used according to the material to be separated and the degree of separation, which will be largely governed by the setting of the plates and the number employed, depth of tank, disposition of delivery chute and etc.

A suitable conveyor such as a belt 73 (Figs. 6, 7, and 1), provided with buckets 74, is adapted to extend into the pit 47 in a direction transversely to the current stream in the tank, for removal of the particles of relatively greater specific gravity. This conveyor is carried at its upper end by a pulley drum 75 mounted on a suitable scaffold 76, (Fig. 1) and at its lower end by a pulley drum 77 mounted in the lower portion 48 of the pit 47 (Fig. 7) and is driven in a manner to be described hereinafter. The buckets 74 are adapted to pass adjacent the lower end of the chute 46 and shields 78—78' are arranged on each side of the chute 46 to guide the particles to the buckets.

A suitable conveyor such as the link belt 79 (Figs. 6, 12 and 13), provided with cleats 80, is adapted to extend into the central pocket of the tank in a direction longitudinally of the current stream in the tank, for removal of the particles of relatively less specific gravity. This conveyor is carried at its upper end by a pulley or sprocket drum 81 (Fig. 1) mounted on a suitable framework 82 to positively engage the link belt, and at its lower end by a pulley drum 83 mounted in the lower portion of the central pocket of the tank and is driven in a manner which will be described hereinafter. The cleats 80 are adapted to pass adjacent the collection chute 84 which is positioned adjacent the separating plate 43 to prevent the particles from falling between this plate and the conveyor passing over the pulley 83. Idle pulleys or rollers 85—86 are supported on the end wall 36 to prevent the loaded upper flight and the lower flight of the conveyor from sagging at its mid-point.

65 *Motive unit and driving train.*

Suitable motive means such for example as the electric motor 87 (Figs. 1 and 2) provides power for driving the separator apparatus. The belt 88 transmits the driving power from the motor 87 to the pulley 89 which is attached to the main power shaft 90 supported in suitable bearings carried by the frame 91 adjacent the main frame 1.

The pulley 92 (Fig. 2) is attached to one end of the power shaft and by means of the belt 93 passing around the idler pulleys 94—94' drives the pulley 95 attached to the shaft 9 which drives the drum 7 by the following means:—The shaft 9 (see Figs. 16 and 17) carries attached thereto by the pin 96 a bevel gear 97 in mesh with a bevel gear 98 carried by the shaft 99 on which are secured driving wheels 100 and 101. The drum 7 is provided with track portions 102 and 102' which rest on the wheels 100 and 101 and on

the idle wheels (Fig. 14) 100' and 101' respectively, in such a manner that as the wheels 100 and 101 are rotated by the mechanism hereinbefore described the drum will be rotated. The idle wheels 100' and 101' are carried on shaft 99' mounted on the side of the drum opposite and in a similar manner to the shaft 99.

The pulley 103 (Fig. 1) is attached to the 10 power shaft 90 and is adapted to drive the conveyor 23 through the belt 104 driving the pulley 105 which drives the belt 106, which in turn drives the pulley 107 attached directly to the pulley 108 which carries the conveyor 15 23. The upper end of conveyor 23 is carried by the pulley 109.

The pulley 110 (see also Fig. 2) is attached to the power shaft 90 and adapted to drive the belt 111 which in turn drives the pulley 20 112 carried by the shaft 113 on which is mounted the eccentric 32 (Fig. 6) provided for shaking the chute 24.

The two conveyors, for removing the separated particles from the liquid tank, and the 25 propeller are driven by the pulley 114 which is secured to the other end of the power shaft 90. The pulley 114 drives a belt 115 which is guided around two idler pulleys 116-116' and drives the pulley 117 which is secured to the line shaft 118 running parallel to the tank and supported in bearings attached thereto. The shaft 118 carries a pulley 119 adapted to 30 drive the belt 120, which operates the pulley 121 secured to the shaft 122 carrying a pinion gear 123, which is in mesh with a wheel gear 124 keyed to the shaft 125 which carries the pulley 75, so that as the shaft 118 rotates the pulley 75 is caused to rotate thereby operate the conveyor 73 in the direction indicated. 35 At the extreme outer end of the shaft 118 a pulley 118' is mounted and the pulley is geared, through suitable connections, to the sprocket drum 81 carrying the link belt 79, and serves to drive the link belt from the shaft 40 118.

The line shaft 118 also carries a cone pulley 126 adapted to drive a jack shaft 127 by means of a cone pulley 128 and cooperating belt 129. The jack shaft 127 is thereby provided with a variable speed mechanism comprising the cone pulleys 126-128 and the belt 129. The jack shaft 127 carries a pulley 130 (Fig. 4) which is adapted to furnish power to the propeller shaft 53 by means of the belt 131 and pulley 132. In this manner a means is provided whereby the speed of the propeller may be varied at will by shifting the belt 129.

Modification.

In Figs. 14 and 15 the apparatus is shown somewhat diagrammatically, mounted on a truck and is adapted to move around from place to place. The mechanical and hydro-dynamical separating units in this modification are of the same general configuration

and character as those previously described except that their relation one to the other has been somewhat changed to better adapt them for use on a truck body. In view of the detailed description of the apparatus hereinbefore described, only a general description of the modification shown in Figs. 14 and 15 is deemed necessary. The truck body is designated as 133 the liquid tank 134 is mounted on one side thereof and is provided with a central pocket 135 and a sump 136. A rotary crusher 137, provided with a feed hopper 138, is mounted to one side of and partly beneath the tank 134. The crusher is also provided with an outlet chute 139 adapted to deliver the crushed material into a hopper 140. A suitable conveyor such as the belt and bucket conveyor 141 is adapted to carry the crushed material up to the grading or screening drum 142, which is mounted in a manner similar to that described hereinbefore and shown in Figs. 16 and 17. Suitable framework carried by the truck body 133 supports the various parts of the apparatus. A chute 143 is provided for carrying away the "fines"; a chute 144 is provided for conducting the material to be hydrodynamically separated to the tank 134 and a portion of the bottom of this chute is provided with a screen 144' to separate dust from the material immediately before it passes into the tank 134; and a chute 145 is provided for carrying away the pieces too large to pass through the perforations or screen of the drum 142. The propulsion wheel 146 is provided for creating a current flow in the tank, and aforesaid horizontal vanes 184-184' and 184'' and vertical vanes 185-185' and 185'' are provided for straightening out the current flow. Adjustable plates 186-186' and 186'' are provided for controlling the directional current flow adjacent the delivery point of the material; all of which are formed in a manner similar to that described heretofore. A conveyor means such as 147 is provided for removing the particles of relatively less specific gravity from the central pocket 135, and a conveyor such as 148 is provided for removing the particles of relatively greater specific gravity from the pit 149 which is arranged adjacent the tank 135 and associated therewith as in the stationary apparatus hereinbefore described.

The motor 150 of the truck is connected with the rear or traction wheels of the truck 120 by means of the drive shaft 151 by any suitable means. The drive shaft 151 carries a worm 152 in mesh with a worm wheel 153 pinned to a power shaft 154 which is supported from the main truck frame in suitable bearings. A clutch collar 155 is mounted on the shaft 154 free to slide axially thereof but adapted to rotate therewith and is engaged by a bell crank 156 operatively connected to a clutch lever 157. A chain 130

sprocket 158 is carried by the shaft 154 held axially thereon but normally free to rotate with respect thereto. The hub of the sprocket 158 is provided with teeth adapted to be engaged by cooperating teeth carried on the clutch collar, so that by moving the clutch lever 157 to the left (Fig. 15) the clutch collar engages the sprocket hub and causes the sprocket 158 to rotate with the shaft 154 thereby driving the chain 159 which engages the sprocket 160 pinned to the line shaft 161 to rotate the same. The shaft 161 is supported by suitable bearings attached to the tank 134 and suitable structural frame-work of the truck.

The propeller wheel 146 is driven directly from the shaft 161.

The conveyor 147 is driven through suitable mechanism such as sprocket 162, chain 163, and sprocket 164 carried by the shaft 165 which also carries the conveyor pulley sprocket drum 166 to positively drive the conveyor 147.

The conveyor 141 is also driven from the shaft 161 by means of the sprocket 167, the chain 168, and the sprocket 169 on the hub of which is carried a spur gear 170 in mesh with a gear 171 mounted on a shaft 172 and which also carries the conveyor pulley or drum 173.

The rotary crusher is driven from the shaft 161 by means of the sprocket 174 attached thereto and the chain 175 which engages the sprocket 176 carried on the shaft of the crusher 137.

The conveyor 148 is driven directly from the shaft 178 (Fig. 14) which corresponds to the shaft 9 of Figs. 16 and 17. This shaft, 178 is adapted to be rotated by a pulley 179 mounted thereon driven by a belt 180 in operative engagement with a pulley 181 mounted on and adapted to rotate with the line shaft 161.

The rotary drum 142, Fig. 15, (corresponding to the drum 7 of Figs. 16 and 17) is driven from shaft 178 in a manner similar to that described in connection with Figs. 16 and 17 hereinbefore described in detail.

50 Operation of stationary apparatus.

Referring particularly to Figs. 2 and 1; the motive means 87 is started and the movable parts of the apparatus are operated through the various power connection hereinbefore described. The adjustable plates in the tank are adjusted to the proper degree to suit the particular material to be operated on, and the degree of separation to be effected, and the propeller speed is adjusted to its proper degree. The material is brought over the crushers by means of the buckets 4-4, and dumped in the crushers. As it is crushed it is delivered to the buckets 6-6 by which means it is delivered to the rotary screen or

drum 7 which separates the "fines" and extra large lumps from the material to be further separated according to its specific gravity. The fines pass out by means of the chute 21 (Fig. 17) and the extra large pieces pass out by means of the chute 20 (Fig. 2) while the material to be operated on to a further degree passes out by means of the chute 22 and is fed along by means of conveyor 23 which delivers it to the shaking screen 24 where the dust passes out through the grating 25 and the remaining material is dumped into the tank at a point adjacent the adjustable plates 64, 65 and 66 (Fig. 6) and the surface of the current. The plates in this instance are shown adjusted at one suitable position for separating coke from slag—the material to be separated being the coke and other partially burnt material from a coal furnace. In this instance the upper flap-plate, 64, is open entirely, the second 85 plate, 65, is partially closed, and the lower plate 66 is preferably closed to a greater extent. It will therefore be seen that the current stream at this point flows with greatest velocity at or near the surface, and decreases in velocity at progressively greater depths. Also at this point the current flow is directed downwardly from a point beneath the surface in increasing degrees at varying degrees of depth. The material of relatively less specific gravity, such as coke, will therefore be carried forward by the swiftly moving surface current and will follow a trajectory which will terminate on the conveyor 79, which will carry the coke out of the tank and deliver it at a suitable collection point. The material of relatively greater specific gravity, such as clinkers, will due to its greater specific gravity, pass through the surface current, and this action 95 will be augmented by the downwardly moving current; so that this material will pass down into the chamber 44. From the chamber 44 the clinkers pass out on the chute 46 (Fig. 7), through the opening in the side 100 34, into the pit 47; and the conveyor buckets 74 remove them to a suitable delivery point.

It will of course be obvious, to those skilled in the art, that the adjustable plates may be set in various positions best adapted to separate various materials composed of particles of varying degrees of specific gravity. The setting herein shown and described is merely one setting deemed satisfactory for separating the particular material under 115 treatment and it is to be understood that the invention is not to be so limited.

The sump formed adjacent the tank end 36 collects sediment from the flowing water which at this point loses much of its velocity due to its sudden change in direction of flow which causes the sediment to settle out. A removable hand hole cover 182 is provided

adjacent the bottom of said sump and provides a means for draining and cleaning out the sump.

5 A second removable hand hole cover 183 is provided in the bottom portion of the central pocket of the tank for draining and cleaning out the pocket.

Operation of portable apparatus.

10 The material to be operated upon is lumped into the hopper 138 feeding it to the crusher 137 from whence it passes through the chute 139 into a hopper 140 and is picked up by the conveyor 141 and delivered to the 15 rotary drum 142 where the "fines" and coarser material are passed out and the material to be separated passes through the chute 144 and is delivered to the flowing liquid at a point downstream from the adjustable plates 184—184'—184". The separated material is removed by the conveyors 147 and 148.

20 While by way of illustration I have described the invention in detail as illustrated 25 in its preferred embodiment for the separation of coke from clinkers, I wish it understood that the apparatus is useful for separating various other substances; such for example as for separating metals from the 30 crushed ore as mined, i. e. by crushing the rock containing ore and separating the metal and/or rock particles rich in metal, from the barren rock.

35 After understanding my invention, it will be obvious to those skilled in the art that various changes and modifications may be made in the arrangement, construction and combination of parts, and certain features omitted according to the desired use of the apparatus, without departing from the spirit 40 or scope of my invention, and I aim in the appended claims to cover all such changes and modifications within the scope of the invention.

45 I claim:—

1. Apparatus for separating granular material composed of particles of different specific gravity, comprising a tank for containing liquid, means for causing the liquid in said tank to flow in a predetermined direction, a series of vanes in said tank for sectionalizing the body of flowing liquid to render the direction of flow of the various portions of the stream more uniform, a series of adjustable plates adjacent the downstream end of said vanes for deflecting the flow in a vertical direction; a chute for conveying said material to said tank at a point adjacent said plates, conveyor means extending transversely of said flow of liquid for removing the particles of relatively greater specific gravity, and conveyor means extending longitudinally of said flow of liquid for removing the particles of relatively less specific gravity.

60 2. Apparatus for separating granular ma-

terial composed of particles of different specific gravity, comprising a tank for containing liquid, means for causing the liquid to flow in a predetermined direction, a vane in said tank for sectionalizing the body of flowing liquid to render the direction of flow of the various portions of the stream more uniform, an angularly adjustable plate within the liquid flow and mounted adjacent the downstream end of said vane for controlling the direction of flow, a chute for conveying the material to said tank, conveyor means for removing the particles of relatively greater specific gravity, and conveyor means for removing the particles of relatively less specific gravity.

65 3. Apparatus for separating granular material composed of particles of different specific gravity comprising a tank for containing liquid, means for causing the liquid to flow in a predetermined direction, a substantially vertical vane in said tank for sectionalizing the body of flowing liquid to render the direction of flow of the various portions of the stream more uniform, a vertically adjustably pivoted plate adjacent the downstream end of said vane for deflecting the flow, delivery means for conveying the material to said tank, conveyor means for removing the particles of relatively greater specific gravity, and conveyor means for removing the particles of relatively less specific gravity.

70 4. Apparatus for separating granular material composed of particles of different specific gravity, comprising a tank for containing liquid, means for causing the liquid to flow at a given rate in a predetermined general direction within said tank, angularly adjustable means for controlling the specific direction of a part of said liquid flow while the rate of flow remains constant, delivery means for conveying the material to said tank and adapted to deliver the material to the liquid flow at a point downstream from said adjustable means, and means for conveying away the material separated by said liquid stream.

75 5. Apparatus for separating granular material composed of particles of different specific gravity, comprising a tank for containing liquid, means for causing the liquid to flow in a predetermined direction, a substantially vertical vane in said tank for sectionalizing the body of flowing liquid to render the direction of flow of the various portions of the stream more uniform, a substantially horizontal vane adjacent the downstream end of said vertical vane, a horizontally disposed vertically adjustable plate supported adjacent said horizontal vane for deflecting the flow, delivery means for conveying the material to said tank, conveyor means for removing the particles of relatively greater specific gravity, and conveyor means for removing the particles of relatively less specific gravity.

80 6. In apparatus for separating granular

130

material composed of particles of different specific gravity, the combination of a tank for containing liquid, a partition within said tank, means in cooperative relation with said 5 partition for causing the liquid in said tank to flow in opposite directions on opposite sides of said partition thereby forming a continuous current stream, vertical directing means adapted to sectionalize and deflect said current in a more uniform flow around one end of said partition to prevent eddies in a substantially horizontal plane, substantially horizontal directing means adapted to prevent eddies in a substantially vertical plane, means 10 for deflecting said current downwardly in different degrees of inclination throughout the depth of said tank, means for delivering said material to the stream after the latter has been so directed and means for removing the 15 separated materials from said liquid.

7. In apparatus for separating granular material composed of particles of different specific gravity, the combination of a tank for containing liquid, means adapted to cause a current flow in said tank in a predetermined direction, delivery means adapted to convey granular material composed of particles of different specific gravity to said tank, means for deflecting portions of said current downwardly in different degrees of inclination at different depths in said tank, at a point adjacent the discharge end of said delivery means.

8. In apparatus for separating granular material composed of particles of different specific gravity, the combination of a tank for containing liquid, means adapted to cause a current flow in said tank in a predetermined direction, delivery means adapted to convey granular material composed of particles of different specific gravity to said tank, means for deflecting portions of said current downwardly in different degrees of inclination at different depths in said tank, said deflecting means being adjacent to and on the upstream 40 side of the point of delivery of the material from said delivery means.

9. Apparatus for separating granular material composed of particles of different specific gravity, comprising a tank for containing liquid, a partition extending longitudinally of said tank, means for causing said liquid to flow in a predetermined direction, means for directing liquid from one side of said partition to the other and for preventing eddy currents in said liquid, deflectors for causing said liquid to flow in vertically diverging directions at different depths, delivery means terminating on the downstream side of said deflector and above the surface 50 of the liquid for delivering the material to be separated, a pit in communication with said tank adjacent to and at a level below said deflector, a first conveyor means for removing material of relatively greater specific gravity 55 from said pit, and a second conveyor means

for removing material of relatively less specific gravity from said tank.

10. Apparatus for separating granular material composed of particles of different specific gravity, comprising a tank for containing liquid, a partition extending longitudinally of said tank, means for causing said liquid to flow in a predetermined direction, means for directing liquid from one side of said partition to the other and for preventing eddy currents in said liquid, a deflector for causing said liquid to flow in vertically diverging directions at different depths, delivery means terminating adjacent said plate and above the surface of the liquid for delivering the material to be separated, transfer means for carrying said granular material to said flowing liquid, a pit in communication with said tank adjacent to and at a level below said deflector, a first conveyor means for removing material of relatively greater specific gravity from said tank.

11. Apparatus for separating granular material composed of particles of different specific gravity, comprising a tank for containing liquid, a partition extending longitudinally of said tank, means for causing said liquid to flow in a predetermined stream direction, means for directing liquid from one side of said partition to the other and for preventing lateral eddy currents in said liquid, deflector means adapted angularly and partially to obstruct the stream for causing said liquid to flow at varying velocities at different depths in said stream, means adapted to deliver material to be separated adjacent said varying flow and the surface of the liquid, a pit in communication with said tank adjacent to and at a level below said varying flow, a first conveyor means for removing material of relatively less specific gravity from said tank.

12. In apparatus for separating granular material composed of particles of different specific gravity, the combination of a tank for containing flowing liquid and provided with a central pocket, a first conveyor means extending from said pocket below the liquid level, for conveying particles from the liquid in said pocket, a pit in communication with said tank through an opening below the liquid level and of greater depth than that of said pocket, a chute adjacent said opening adapted to direct particles from said tank into said pit by gravity, and conveyor means extending from below the liquid level in said pit to an exterior point for conveying particles from said pit.

13. The method of separating granular material composed of particles of different specific gravity which consists in delivering said material so treated to a body of water ad-

ja cent the surface thereof, causing said water to flow in a continuous current stream, controlling said current flow beneath the surface thereof at a plurality of different depths in such manner that the forward velocity of said current flow will be greater at the surface and progressively less at greater depths adjacent the point of delivery of said material whereby

said material will be separated into a plurality of groups according to specific gravity, ¹⁰ and removing each group separately from said liquid.

In testimony whereof I have signed my name to this specification.

ANTHONY R. SILVERSTON.
